UNITED STATES PATENT OFFICE.

THOMAS LEGGETT STURTEVANT, OF QUINCY, AND THOMAS J. STURTEVANT, OF WELLESLEY, MASSACHUSETTS.

ROLL CRUSHING-MILL.

SPECIFICATION forming part of Letters Patent No. 777,448, dated December 13, 1904.

Application filed June 1, 1904. Serial No. 210,735. (No model.)

To all whom it may concern:

Be it known that we, THOMAS LEGGETT STURTEVANT, residing at Quincy, and THOMAS J. STURTEVANT, residing at Wellesley, in the county of Norfolk and State of Massachusetts, citizens of the United States, have invented certain new and useful Improvements in Roll Crushing-Mills, of which the following is a specification, reference being had therein to the accompanying drawings.

This invention relates to a roll crushing-mill such as is shown in our application No. 180,215, filed November 7, 1903. In the crushing-mill of our said application the shafts carrying the crushing-rolls are mounted in bearing-boxes, which are movably held in pedestals or carriers by springs which press against the said boxes in such a manner as to force the crushing-rolls toward each other, but which springs will yield more or less to cushion the rolls, and thus avoid objectionable jars or shocks. In order to provide for the convenient insertion or removal of the bearing-boxes from their carriers or pedestals, it is necessary to remove the pressure of the cushioning-springs against the said boxes, and the present invention relates to means whereby this may be effected.

In the accompanying drawings, Figure 1 is a longitudinal sectional view of a roll crushing-mill embodying the present invention. Figs. 2 and 3 are detail views illustrating slightly different forms of the invention from that shown in Fig. 1.

Referring to the drawings, 12 denotes the base or frame of the machine, on which in the present instance are adjustably mounted the open-topped carriers or pedestals 14 for the bearing-boxes 15, in which the shafts 16 of the crushing-rolls 17 are mounted. Nests of powerful coil-springs 18 are placed in recessed portions of the bearing carriers or pedestals 14, said springs pressing against the bearing-boxes 15 in such a manner as to force the crushing-rolls toward each other. In order to insert the bearing-boxes 15 in their carriers or pedestals 14 or to remove said boxes from said carriers or pedestals when the removable covers with which the latter are

provided have been taken off, it is necessary that the pressure of the springs 18 against said boxes be removed. This is effected in the construction shown in Fig. 1 by screw-bolts 19, provided at their inner ends with disks or flanges 20, against which the said springs bear, the outer ends of said bolts, which pass loosely through holes in the walls of the pedestals or carriers 14, being screw-threaded for the reception of nuts 21, which can be turned to compress the springs 18, when desired, for the purpose of relaxing or removing the pressure of said springs normally transmitted to the boxes 15 through the disks or flanges 20.

In the construction shown in Fig. 2 the springs 18 bear directly against the bearing-box 15 and are confined in their chamber in the carrier or pedestal 14 by a screw-cap 22, provided with holes for the insertion of a suitable wrench or tool by which said screw-cap may be removed from the carrier or pedestal, thereby removing the pressure of the springs from the bearing-box.

In the construction shown in Fig. 3 the springs 18 are held in the chamber in the carrier or pedestal by a compression-plate 23, held in place by screw-bolts 24, tapped in portions of the carrier or pedestal, so that by screwing out the said bolts the compression-plate may be adjusted or removed to relax or remove the pressure of the springs from the bearing-box 15.

In the construction shown in Fig. 1 the pedestals or carriers 14, in which the bearing-boxes are inserted, are adjustably mounted on the frame or base 12 of the machine, so that they may be moved back and forth by the screw tie-rods 25, provided with worm-wheels 26, by which they may be turned from a worm-shaft 27, the threaded ends of said screw tie-rod engaging nuts 28, suitably bolted to the said pedestals or carriers, as shown and described in our application hereinbefore referred to. It will be understood, however, that the present invention is applicable to bearing-box carriers or pedestals which may be fixed to the frames of the machines, as well as bearing-box carriers or pedestals which are

adjustably mounted on the frames of the machines, as in the construction herein shown.

Having thus described our invention, we claim, and desire to secure by Letters Patent—

- 5 1. In a roll crushing-machine, the combination with a pair of crushing-rolls and shafts by which said rolls are carried, of bearing-boxes for said shafts, open-topped carriers or pedestals supporting said bearing-boxes and suitably recessed, said boxes being movably mounted in said carriers or pedestals, springs in the recessed portions of said carriers or pedestals for yieldingly forcing said crushing-rolls toward each other, and means for relaxing or removing the pressure of said springs from said bearing-boxes when it is desired to remove said boxes from said open-topped carriers or pedestals, or insert said boxes therein.
- 10 15 2. In a roll crushing-machine, the combination with a pair of crushing-rolls and shafts by which said rolls are carried, of bearing-boxes for said shafts, open-topped carriers or pedestals, or insert said boxes therein.
- 20 25 30 35 40

pedestals supporting said bearing-boxes and suitably recessed, said boxes being movably mounted in said carriers or pedestals, springs in the recessed portions of said carriers or pedestals for yieldingly forcing said crushing-rolls toward each other, and means for relaxing or removing the pressure of said springs from said bearing-boxes when it is desired to remove or replace said boxes, said means consisting of screw-bolts encircled by said springs and passing loosely through holes in the outer walls of said carriers or pedestals and provided with nuts at their outer projecting ends, said bolts also having, at their inner ends, flanges or disks against which the inner ends of the springs impinge.

In testimony whereof we affix our signatures in presence of two witnesses.

THOMAS LEGGETT STURTEVANT.

THOMAS J. STURTEVANT.
